UNITED STATES PATENT OFFICE.

ELI BROTHERS, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

RELASTING MACHINE.

Application filed February 2, 1917. Serial No. 146,250.

To all whom it may concern:

Be it known that I, ELI BROTHERS, a citizen of the United States, residing at Lynn, in the county of Essex and State of Massachusetts, have invented certain Improvements in Relasting Machines, of which the following description, in connection with the accompanying drawings, is a specification, like reference characters on the drawings indicating like parts in the several figures.

This invention relates to mounting shoes on lasts. Since this is an operation extensively performed in the manufacture of turn shoes, the invention is herein illustrated in its relation to a shoe of this type, but it will be understood that the invention is not thus restricted in its applicability and that a machine in which the novel features of the invention are embodied may be used with advantage irrespective of the particular type of the shoe.

When a last is inserted in a shoe at an intermediate stage in the process of manufacture, as for example in a turn shoe after the shoe turning operation has been performed, it is important for the final shape of the shoe, which is determined in large measure by the last, that the last fit closely within the shoe and even have a tendency to dis-tend some portions of the upper. The relasting operation, as heretofore generally performed by hand, has accordingly been a relatively slow and laborious one. It has been, moreover, a common practice in relasting turn shoes to insert the forepart of the last loosely in the shoe and while grasping the shoe about the forepart to strike the rear end of the last forcibly upon the work bench or upon a block provided for the purpose. A frequent result of this operation is that the rear end of the last is battered out of shape and the last has to be discarded.

An object of this invention is to provide for the operation of mounting a shoe on a last readily and quickly, without damage to the last or the shoe. To this end the invention provides, as an important feature, in combination with shoe engaging means, a novel construction and arrangement of mechanism for imparting movement to a last to force it into a shoe engaged by said means. The construction shown as an illustrative embodiment of the invention comprises a last supporting member mounted on a plunger

which is movable to force the last in the direction of the bottom of a shoe in which the last is partially inserted, and means for causing said member to swing the last in the direction of the toe end of the shoe to force the last into the forepart of the shoe.

A further feature of the invention consists in the combination with means for forcing a last into a shoe, of novel means for determining the position of the shoe during the movement of the last. In the illustrative construction a shoe horn is arranged for engagement with the interior of the heel end portion of a shoe between the shoe and the last to oppose resistance to movement of the shoe with the last, leaving substantially all portions of the exterior of the shoe free for engagement by the hands of the operator. In accordance with a feature of the invention, moreover, a horn is provided of such shape that upon withdrawal of the horn from the shoe through relative movement of the parts of the machine the parts may be returned to starting position without causing the horn to catch upon the shoe and remove it from the last, thus permitting the machine to be power driven.

The invention also provides, as a further feature, novel means for moving both a shoe and a last to effect the relasting operation, the illustrative embodiment comprising a shoe horn and means for imparting operative movement thereto to draw the shoe over the last in co-operation with means for moving the last into the shoe.

These and other features of the invention, including certain details of construction and combinations of parts, will now be described with reference to the accompanying drawings and pointed out in the claims.

In the drawings:

Fig. 1 is a view in side elevation of a machine in which the invention is embodied, showing a shoe in position to be operated upon by the machine.

Fig. 2 is a view similar to Fig. 1 on an enlarged scale, showing the upper portion of the machine with the parts as positioned at the end of an operation upon a shoe and before returning to starting position, a portion of the machine being shown in vertical section, and

Fig. 3 is a view partly in side elevation and partly in vertical section of a machine

embodying certain features of construction alternative with features illustrated in Figs. 1 and 2.

The operative parts of the machine (Figs. 1 and 2) are supported upon a frame or column 2 which, in the construction shown, is adapted to rest upon the floor. The support for the principal operative parts may, however, if desired, be of suitable size and shape to permit it to be mounted upon a work bench. Mounted for vertical reciprocating movement in the column 2 is a plunger 4 which serves to impart operative movement to shoe and last engaging instrumentalities to be hereinafter described. The plunger 4, in the construction shown, is arranged to be driven from a power operated pulley 5 through a friction clutch the member 6 of which is splined on a shaft 7 on which the pulley 5 is loosely mounted. The plunger 4 is connected to the shaft 7 by means of a pitman 8 and reduction gearing indicated generally by 9. The clutch member 6 is moved lengthwise of the shaft 7 by means of a lever 10 and a reciprocating rod 11, a spring 12 which bears on a collar 13 on the rod serving to position the member 6 normally out of engagement with the co-operating clutch member on the face of the pulley 5. For moving the rod 11 against the resistance of the spring a foot treadle 14 is provided which carries a member 15 having the form of a bell crank pivoted on the treadle and held normally by means of a spring 16 with its lower arm in position for endwise engagement with the collar 13, as shown in Fig. 1. A dog 17 on the upper arm of the member 15 is so positioned as to be engaged at a certain time in the cycle of operations of the machine by a wedge shaped projection 18 on the side of that member of the series of gears 9 to which the pitman 8 is pivoted. A spring 19 tends to raise the treadle 14 and position it normally in engagement with a stop 20 on the column 2.

As the parts are positioned in Fig. 1, the operator has depressed the treadle 14, thereby causing the member 15 to slide the rod 11 rearwardly and bring the clutch member 6 into engagement with the co-operating member on the pulley 5 for imparting relatively slow movement to the pitman 8 to raise the plunger 4. It will be understood that the cycle of operations of the machine is completed by a single reciprocation of the plunger 4 effected by a single revolution of that gear 9 on which the pitman 8 is pivoted, which corresponds to a plurality of revolutions of the shaft 7. The construction shown requires that the operator keep the treadle 14 continuously depressed during the cycle of operations. Immediately prior to the arrival of the plunger 4 again in its lowermost position

the projection 18 on the gear engages the dog 17 and swings the bell crank 15 out of endwise engagement with the collar 13, thus permitting the spring 12 to act through the rod 11 and the lever 10 to disconnect the clutch. The weight of the parts will then cause the plunger 4 and the connected mechanism to come to rest with the plunger in its lowermost position, after which the treadle may be released to position the member 15 again in operative relation to the collar 13.

It will be readily understood that various mechanisms, of which the construction shown is merely illustrative, may be employed for effecting a cycle of operations of the machine, and that the machine, moreover, may be readily arranged for operation by foot power, if so desired.

Mounted on a pivot 21 extending transversely of the plunger 4 at the upper end of the plunger is a last supporting member 22 comprising a bell crank lever having a substantially upright arm provided with a last pin 24 at its upper end, the other arm of the bell crank, in the construction shown, extending forwardly with a downward curve and having pivoted to its outer end a block 26 which is arranged to slide in an inclined guideway 28 formed in a bracket 30 on the column 2. It will be evident that in this construction the engagement of the block 26 with the guideway 28 will cause the last supporting member 22 to turn about its pivot 21 during the upward movement of the plunger 4 with the member 22 in a direction which is approximately perpendicular to the plane of the last button, the extent of the turning movement of the member 22 depending upon the angular relation of the guideway 28 to the line of movement of the plunger, and such turning movement serving to swing the last pin 24 forwardly, as illustrated in Fig. 2.

Co-operating with the parts hereinbefore described to cause a shoe to be drawn over a last on the pin 24 during the upward and forwardly swinging movement of the last, is a shoe engaging member comprising a shoe horn 32 having a concave face on the side toward the heel end of the last and preferably provided upon its outer convex side with a covering 34 of leather or similar material to increase the friction between the horn and the interior of the shoe. The horn is arranged to project slightly above the bottom of the last when the parts of the machine are in starting position as shown in Fig. 1, and the tip of the horn is preferably flared outwardly, as shown, to provide a lip 36 in order to insure more effective engagement of the horn with the shoe in the final stage of the relasting operation and also for a purpose which will be subsequently explained. The horn 32 is formed on the upper end of an arm 38 the lower end

of which is pivoted at 40 to links 42 which are pivotally connected to the lower end of a lever 44 pivoted in turn at 46 to a bracket 48 on the rear of the column 2. The pivot 40 is provided with blocks arranged to slide in guideways 50 in opposite sides of the bracket 48, whereby the arm 38 and the links 42 are supported. A link 52 serves to connect the upper end of the lever 44 to the pivot 21 on the plunger 4. The bracket 48 is shaped to provide a guideway 54 between the two side portions in which the guideways 50 are formed, the guideway 54 being arranged for engagement with a spring plunger 56 movable in a socket in the lower end of the arm 38. The spring plunger thus tends to swing the arm 38 in one direction about the pivot 40 and serves to hold the horn 32 yieldingly in engagement with the rear end of a last mounted on the pin 24. A projection 57 on the lower end of the arm 38 at the opposite side of the pivot 40 from the plunger 56 is arranged to engage the guideway 54 when no last is mounted on the pin 24 and thus limit the swinging movement of the horn toward the last pin and prevent it from striking the pin.

It will be evident from the preceding description that an upward movement of the plunger 4 will cause the link 52 to impart a swinging movement to the lever 44 in a direction to slide the pivot 40 by which the arm 38 is connected to the links 42 inwardly, thus moving the arm 38 bodily forward in unison with the forward swinging movement of the last and maintaining the horn in such relation to the last as to cause the lip 36 to continue to project outwardly from the rear end of the last.

In the operation of the machine constructed as shown in Figs. 1 and 2, the operator mounts a last on the pin 24 and draws a shoe over the last as far as he can conveniently do so by hand, positioning the rear end of the shoe over the outer end portion of the horn 32. He then actuates the clutch by depressing the treadle 14, causing the plunger 4 to be raised and the parts to assume the positions indicated in Fig. 2 at the end of the upward movement of the plunger. During this operation the last is raised and swung forwardly in the manner hereinbefore described, while the horn 32, through its forward movement as above described, remains in substantially the same location relative to the shoe until finally disengaged from between the shoe and the last by the upward movement of the last. The rear end portion of the last, at the beginning of its upward movement, slides over the smooth inner surface of the horn without substantial frictional engagement with the shoe, while the frictional engagement between the shoe and the leather covering on the outer surface of the horn, assisted by the rearward

projection of the lip 36, serves to restrain the rear end of the shoe substantially from upward movement with the last. The operator, moreover, will naturally use his hands to supplement the operation of the machine, pressing the shoe rearwardly and downwardly on the last and thus further insuring that the shoe shall remain continuously in engagement with the horn. As the upward movement of the plunger 4 continues, the parts finally arrive in the position indicated in Fig. 2, in which position the last is firmly seated in the shoe and the shoe and the last are withdrawn from the horn in such manner as to cause the horn to be positioned outside of the shoe. The horn having been moved bodily forward in unison with the forward movement of the last, the lip 36 will now be outwardly directed with relation to the upper rear edge of the shoe, and as the plunger 4 is lowered in the continued movement of the parts the last will return to its starting position without any tendency for the shoe to catch upon the horn in such manner as to cause the shoe to be pushed off from the last. After the parts of the machine have been returned to starting position as hereinbefore explained, the shoe and the last may be removed from the last pin 24.

In Fig. 3 is shown a construction which is substantially the same as that shown in the other figures with the exception of the shoe horn operating means. In this construction the horn is initially positioned to project considerably farther above the bottom of the last than in the previously described construction, and is given, moreover a downward movement simultaneously with a portion of the upward movement of the last. To this end the horn is mounted upon a slide 58 vertically movable in guideways in a bracket 60 on the column 2, the slide having rack teeth 62 in engagement with a pinion 64 which is mounted on the bracket 60 and engages on its opposite side the teeth of a rack 66 which is mounted for limited vertical sliding movement on guides 68 on the plunger 4. The arm 38 which carries the horn is pivoted at 70 to the upper end of the slide 58, and the horn is held in engagement with the last through the action of a spring 72 confined between projections 74 and 76 formed on the slide 58 and the arm 38 respectively. A bolt 78 projecting upwardly from the projection 74 serves as a guide for the spring 72, and a nut 80 on the bolt acts as a stop for the projection 76 to limit movement of the horn 32 toward the pin 24 when no last is mounted on the pin and prevent the horn from striking the pin. When the parts of the machine are in their idle position, as shown in Fig. 3, a lug 82 on the plunger 4 at the upper end of the guides 68 engages the upper end of the rack slide 66

and through the pinion 64 holds the slide 58 in its uppermost position. At the lower end of the guides 68 the plunger 4 carries a lug 84 which operatively engages the rack 66 when the plunger is moved upwardly, as will be hereinafter explained.

In the use of the construction shown in Fig. 3 the last and the shoe are positioned in substantially the same relation to the parts 10 of the machine as in the construction of Figs. 1 and 2, the shoe, however, engaging the horn primarily about midway of the length of the horn. By reason of the provision for lost motion between the lug 84 15 and the rack 66 the plunger 4 is moved upwardly a limited distance without effecting a movement of the horn which will remain substantially stationary in consequence of the tendency of the slides 58 and 66 to preserve a balanced relation, as well as the friction of the parts and the frictional engagement of the shoe and the last with the horn. Such limited movement serves to increase 20 the pressure of the shoe against the outer surface of the horn. The lug 84 will then engage the lower end of the rack 66 and during the continued upward movement of the plunger the rack 66 also will be moved upwardly, thus imparting through the pinion 30 64 and the rack 58 a downward movement to the horn 32 simultaneously with the upward and forwardly tipping movement of the last. The horn thus acts through frictional engagement with the shoe to pull the 35 shoe downward over the heel end of the last and hence also rearwardly on the last while the last is being forced into the shoe by the action of the plunger. During this movement the lip 36 comes into engagement with the shoe and serves further to insure effective engagement of the horn with the shoe. During the continued downward movement 40 of the horn 32 the horn is finally withdrawn from the shoe and the lip 36 will then assume a relation to the shoe substantially as in the 45 construction shown in Fig. 2, to permit the parts of the machine to return to starting position without removing the shoe from the last.

It will be evident from the foregoing description that the invention provides means whereby the mounting of a shoe on a last, with the last positioned closely in both the forepart and the heel portion of the shoe, 55 may be readily effected in one continuous operation, and that the exterior portions of the shoe, moreover, are left free to be engaged by the hands of the operator, thus enabling him to retain his hold upon the shoe continuously and facilitating the removal of the shoe from the machine without loss of time, as well as enabling the operator to supplement the action of the machine by hand pressure on the shoe if such action is 60 desirable in the case of any shoe presented

for treatment. It will be evident, moreover, that it is immaterial to the operation of the machine whether the sole be unattached at its heel end, as in the nailed heel seat type of turn shoe shown, or attached to the upper 70 at the time when the relasting operation is performed.

Having described the invention, what I claim as new and desire to secure by Letters Patent of the United States is:

1. A machine of the class described having, in combination, a last engaging member arranged to engage a last the forepart of which is partially inserted within the forepart of a shoe, operating means for said member having a right line movement approximately perpendicular to the plane of and toward the bottom of a last engaged by said member to carry the member in a direction approximately perpendicular to said plane and toward the bottom of a shoe partially mounted on the last, means for causing substantially simultaneously a movement of the member at an angle to the direction of movement of said operating means effective to force the forepart of the last toward the toe end of the shoe, and shoe engaging means arranged to cooperate with said member to cause the last to be inserted in the shoe.

2. A machine of the class described having, in combination, a last engaging member, means for operating said member to force a last into a shoe comprising mechanism for imparting a right line movement to the member in a direction approximately perpendicular to the plane of and toward the bottom of a last engaged by said member and for simultaneously moving the member to swing the engaged last in the direction of the toe of the shoe, and shoe engaging means arranged to co-operate with said member to cause the last to be forced into the shoe.

3. A machine of the class described having, in combination, a last engaging member, a plunger on which said member is pivoted, means for moving the plunger lengthwise, means for causing said member to swing the last bodily in the direction of its toe end during said movement of the plunger, and means for engaging a shoe in which the last is partially inserted, said shoe engaging means being arranged to co-operate with said member to cause the last to be forced into the shoe.

4. A machine of the class described having, in combination, a last engaging member, a support on which said member is mounted, the member being movable relatively to the support, means connected to said support for operating it to move the last engaged by said member in a direction toward the bottom of a shoe within the forepart of which the forepart of said last is

- partially inserted, means for operating said member through said movement of the support to cause the last to be moved also in the direction of the toe of the shoe, and shoe 5 engaging means arranged to cooperate with said member to cause the last to be forced into the shoe.
5. A machine of the class described having, in combination, a last engaging member, a support on which said member is pivoted, means for operating said support to move a last engaged by said member in a direction toward the bottom of a shoe within the forepart of which the forepart of said 10 last is partially inserted, an arm projecting from said member, means for cooperating with said arm to cause the last to be swung in the direction of its toe end during its movement toward the bottom of the shoe, and shoe engaging means arranged to cooperate with said member to cause the last to be forced into the shoe.
6. A machine of the class described having, in combination, a last engaging member, a support on which said member is pivoted, means for operating said support to move a last engaged by said member in a direction toward the bottom of a shoe within the forepart of which the forepart of said 15 last is partially inserted, means providing a guideway at an angle to the line of movement of the support, means projecting from said member and engaging the guideway to cause the member to swing the last in the direction of the toe of the shoe during said movement of the support, and shoe engaging means arranged to co-operate with said member to cause the last to be forced into the shoe.
7. A machine of the class described having, in combination, a last supporting member, means for operating said member to raise the last and simultaneously to swing the last in the direction of its toe end, and shoe engaging means arranged to co-operate with said member to cause the last to be forced into a shoe.
8. A machine of the class described having, in combination, a last supporting member, a support on which said member is pivoted, means for moving said support upwardly, means for swinging said member about its axis during the upward movement of the support to tip the last in the direction of its toe end, and means for restraining the heel portion of a shoe in which the last is partially inserted from upward movement to cause the last to be forced into the shoe.
9. A machine of the class described having, in combination, a last supporting member provided with a pin to engage in the spindle hole of a last, a plunger on which said member is pivoted, means for moving the plunger upwardly, means for causing said member to swing about its axis during 60 the upward movement of the plunger to incline the last pin forwardly, and means for restraining the heel portion of a shoe in which the last is partially inserted from upward movement to cause the last to be forced 70 into the shoe.
10. A machine of the class described having, in combination, a vertically movable plunger, a last supporting member pivoted on the upper end of said plunger and having a substantially upright pin to engage in the spindle hole of a last, means for moving the plunger upwardly, an arm projecting laterally from said member, means for operating said arm to cause the last to be swung 75 in the direction of its toe end during the upward movement of the plunger, and means for restraining the heel portion of a shoe in which the last is partially inserted from upward movement to cause the last to be forced 80 into the shoe.
11. A machine of the class described having, in combination, last engaging means, mechanism for operating said means to force a last into a shoe, and means arranged to operate solely by frictional engagement with the interior of the shoe for opposing resistance to movement of the shoe with the last and of itself wholly effective to restrain the shoe from movement with the 85 last when the latter is forced into the shoe by said mechanism.
12. A machine of the class described having, in combination, last engaging means, mechanism for operating said means to force a last into a shoe, and means for opposing resistance to movement of the shoe with the last constructed and arranged to engage the interior of the shoe while leaving substantially all portions of the bottom of the shoe 90 free to be engaged by the hands of the operator.
13. A machine of the class described having, in combination, last engaging means, mechanism for operating said means to force a last into a shoe, and means comprising a shoe horn arranged to be positioned between the heel end of the last and the shoe to oppose resistance to movement of the shoe with the last while leaving substantially all 95 portions of the exterior of the shoe free to be engaged by the hands of the operator.
14. A machine of the class described having, in combination, means for supporting a last bottom upward, mechanism for moving said supporting means to force the last into a shoe in which the last is partially inserted, a shoe horn, and means for positioning the horn in engagement with the rear end of the last with its end portion 100 projecting initially above the last bottom and its outer side in engagement with the shoe to cause the horn to oppose resistance to movement of the shoe with the last.
15. A machine of the class described hav- 105
- 110
- 115
- 120
- 125
- 130

ing, in combination, last engaging means, a shoe horn, and mechanism for effecting relative movement of said means and the horn to cause a last to be inserted in a shoe said horn having an outwardly directed lip on its end portion to insure effective engagement with the shoe.

16. A machine of the class described having, in combination, last engaging means, mechanism for operating said means to force a last into a shoe, and a shoe horn for engaging the interior of the heel end of the shoe to oppose resistance to movement of the shoe with the last, said horn having its end portion outwardly flared to insure effective engagement with the shoe.

17. A machine of the class described having, in combination, last engaging means, mechanism for operating said means to force a last into a shoe, means for engaging the heel end portion of the shoe, and mechanism for operating said shoe engaging means to force the shoe over the last simultaneously with said operation of the last engaging means.

18. A machine of the class described having, in combination, last engaging means, mechanism for operating said means to force a last into a shoe, a shoe horn arranged for engagement with the interior of the heel end portion of the shoe, and mechanism for operating said horn to pull the shoe over the last simultaneously with the movement of the last into the shoe.

19. A machine of the class described having, in combination, last engaging means, a shoe horn arranged for engagement with the interior of the heel end portion of a shoe in which the last is partially inserted, and mechanism for moving said means and the horn simultaneously to cause the last to be inserted in the shoe.

20. A machine of the class described having, in combination, last engaging means, mechanism for operating said means to force a last into a shoe, shoe engaging means, and a connection between said mechanism and the shoe engaging means to cause said last named means to pull the shoe over the last simultaneously with the movement of the last into the shoe.

21. A machine of the class described having, in combination, last engaging means, mechanism for operating said means to force a last into a shoe, a shoe horn arranged for engagement with the interior of the heel end portion of the shoe, and a connection between said mechanism and the horn to cause the horn to move the shoe relatively to the last during the movement of the last into the shoe.

22. A machine of the class described having, in combination, a last engaging member, a shoe horn, and mechanism connecting said member and the horn for moving them

in unison to cause a last to be inserted in a shoe.

23. A machine of the class described having, in combination, last engaging means, mechanism for operating said means to move a last simultaneously toward the bottom and toward the toe end of a shoe in which the last is partially inserted, and means for engaging the heel end portion of the shoe and pulling the shoe over the last simultaneously with said movement of the last.

24. A machine of the class described having, in combination, last engaging means, mechanism for operating said means to swing a last in the direction of the toe end of a shoe in which the last is partially inserted, a shoe horn arranged to engage the interior of the heel end portion of the shoe, and means for operating said horn to draw the shoe over the last simultaneously with said swinging movement of the last.

25. A machine of the class described having, in combination, last engaging means, mechanism for operating said means to force a last into a shoe, means for engaging the rear end portion of the shoe upper, and mechanism for operating said shoe engaging means to pull the rear end portion of the shoe over the last simultaneously with the movement of the last into the shoe.

26. A machine of the class described having, in combination, last engaging means, mechanism for operating said means to force a last forwardly into the forepart of a shoe, and means for engaging the rear end portion of the shoe upper and pulling the shoe over the heel of the last simultaneously with the movement of the last into the forepart of the shoe.

27. A machine of the class described having, in combination, last engaging means, mechanism for operating said means to force a last into a shoe, means arranged for frictional engagement with the interior of the heel end portion of the shoe, and mechanism for operating said shoe engaging means to draw the heel end portion of the shoe over the last simultaneously with the movement of the last into the shoe.

28. A machine of the class described having, in combination, last engaging means, mechanism for operating said means to force a last into a shoe, a shoe horn arrangement to project initially into the shoe beyond the bottom of the last, and means for operating said horn to draw the heel end portion of the shoe over the last and then to withdraw the horn from the shoe.

29. A machine of the class described having, in combination, last supporting means, a shoe horn arranged to project initially beyond the bottom of a last mounted on said means and to engage the interior of the heel end portion of a shoe in which the last is partially inserted, means for operat-

ing said last supporting means to force the last into the shoe, and means for moving the horn simultaneously in a direction to draw the heel end portion of the shoe over the last.

30. A machine of the class described having, in combination, last engaging means, a shoe horn, and means for moving said means and the horn simultaneously in substantially opposite directions to cause a last to be inserted in a shoe.

31. A machine of the class described having, in combination, means for supporting a last bottom upward, a shoe horn arranged to project initially above the bottom of the last in engagement with the heel end of the last, means for moving said supporting means upwardly and forwardly to force the last into a shoe positioned with its heel end over the horn, and means for moving the horn downwardly to draw the heel end portion of the shoe over the last.

32. A machine of the class described having, in combination, last engaging means, shoe engaging means, and mechanism for imparting movement to both said means to cause a last to be inserted in a shoe, said mechanism being constructed and arranged to cause the last to move a limited distance prior to movement of said shoe engaging means.

33. A machine of the class described having, in combination, last engaging means, mechanism for operating said means to force a last into a shoe, shoe engaging means, and connections between said mechanism and the shoe engaging means for moving said last named means in a direction to force the shoe over the last, said connections including provision for lost motion to cause a limited movement of the last to be effected prior to movement of the shoe engaging means.

34. A machine of the class described having, in combination, last engaging means, mechanism for operating said means to force a last into a shoe, a shoe horn, and connections between said mechanism and the horn for moving the horn in a direction to draw the heel end of the shoe over the last, said connections including provision for lost motion to cause a limited movement of the last to be effected to tighten the shoe over the horn prior to movement of the horn.

35. A machine of the class described having, in combination, last supporting means, a shoe horn, and means for moving the horn in the direction of the height of the last to draw a shoe over the last, said horn having a lip on its end portion projecting rearwardly of the shoe to insure effective engagement of the horn with the shoe.

36. A machine of the class described having, in combination, last engaging means, mechanism for operating said means to

force a last into a shoe, a shoe horn arranged to engage the interior of the heel end portion of the shoe to restrain the shoe from movement with the last, and yielding means for positioning said horn in engagement with the heel end of the last.

37. A machine of the class described having, in combination, last engaging means, mechanism for operating said means to force a last into a shoe, a shoe horn arranged to engage the rear end of the last, means tending to move the horn in the direction toward the last engaging means, and to hold the horn yieldingly in engagement with the last, and means for limiting movement of the horn in said direction when the last is removed.

38. A machine of the class described having, in combination, last engaging means, a shoe horn, and mechanism for effecting relative movement of said means and the horn to cause a shoe to be mounted on a last and the horn to be withdrawn from the shoe and then to cause said parts to return to initial position, said horn having its end portion outwardly flared to cause the horn to clear the shoe in said return movement.

39. A machine of the class described having, in combination, last engaging means, a shoe horn, a spring tending to move the horn toward said means, and mechanism for effecting relative movement of said means and the horn to cause a shoe to be mounted on a last and the horn to be withdrawn from the shoe and then to cause said parts to return to initial position, said horn having its end portion shaped to cause the horn to clear the shoe in said return movement.

40. A machine of the class described having, in combination, last supporting means, a shoe horn, and means for moving the horn to draw a shoe over a last on said supporting means and withdraw the horn from the shoe and for then returning the horn to its initial position, the horn having its end portion outwardly flared to prevent it from catching upon the outside of the shoe.

41. A machine of the class described having, in combination, means for supporting a last partially inserted in a shoe comprising a pin to enter the spindle hole of the last, means for moving said supporting means substantially in the direction of the height of the last and for simultaneously tipping the pin in a direction toward the toe end of the shoe, and means for engaging the shoe arranged to co-operate with said last supporting means to cause the last to be forced into the shoe.

42. A machine of the class described having, in combination, last engaging means, means arranged to be interposed loosely between the heel end of the last and the interior of a shoe in which the last is partially inserted in a direction approximately per-

pendicular to the plane of and toward the bottom of the last means to cause the last to be forced into the shoe.

43. A machine of the class described having, in combination, means for engaging a last partially inserted in a shoe, a shoe horn arranged to project initially across the plane of the heel seat of the last and having a rearwardly directed lip to engage the shoe, and means for operating said last engaging means and shoe horn to cause the last to be forced into the shoe.

44. A machine of the class described having, in combination, means for engaging a last partially inserted in a shoe, means arranged to be interposed loosely between and in frictional engagement with the last and the shoe, and mechanism for operating both said means to cause the last to be forced into the shoe and then to return said means to starting position.

45. A machine of the class described having, in combination, means for engaging a last partially inserted in a shoe, a shoe horn arranged to be interposed between and in frictional engagement with the heel end of the last and the shoe, and mechanism for operating said last engaging means and the shoe horn to cause the last to be forced into the shoe, said mechanism being constructed to withdraw the horn from the shoe and to return the last engaging means and the horn to starting position.

46. A machine of the class described having, in combination, means for supporting bottom upward a last and a shoe with the last partially inserted in the shoe and with its toe end pointing toward the operator's working position, and means for operating said supporting means to force the last into the shoe constructed and arranged to tip the last forwardly while permitting the operator to press downwardly and rearwardly upon the shoe.

45 47. A machine of the class described hav-

ing, in combination, means for supporting bottom upward a last and a shoe with the last partially inserted in the shoe and with its toe end pointing toward the operator's working position, means for forcing the last both upwardly and toward the toe end of the shoe while permitting the operator to press downwardly and rearwardly on the shoe, and means for engaging the rear end portion of the shoe upper to restrain the heel end of the shoe from upward movement with the last.

48. A machine of the class described having, in combination, means for supporting bottom upward a last and a shoe with the last partially inserted in the shoe, means for forcing the last both upwardly and also forwardly toward the toe end of the shoe, and means for engaging the rear end portion of the shoe upper to restrain the heel end of the shoe from upward movement with the last.

49. A machine of the class described having, in combination, a last engaging member arranged to engage a last the forepart of which is partially inserted within the forepart of a shoe, operating means for said member having a right line movement approximately perpendicular to the plane of and toward the bottom of the last engaged by said member to carry the member in a direction approximately perpendicular to said plane and toward the bottom of a shoe partially mounted on the last, means effective through the right line movement of said member for swinging said member in a direction to force the forepart of the last toward the toe end of the shoe, and shoe engaging means arranged to co-operate with said member to cause the last to be inserted in the shoe.

In testimony whereof I have signed my name to this specification.

ELI BROTHERS.

Certificate of Correction.

It is hereby certified that in Letters Patent No. 1,470,613, granted October 16, 1923, upon the application of Eli Brothers, of Lynn, Massachusetts, for an improvement in "Relasting Machines," errors appear in the printed specification requiring correction as follows: Page 2, line 102, for the word "button" read *bottom*; page 7, line 118, claim 41, strike out the words "substantially in the direction of the height" and insert instead *in a direction approximately perpendicular to the plane of and toward the bottom*; same page, line 130, claim 42, beginning with the word "in" strike out all to and through the word "last", first occurrence, page 8, line 2, and insert instead the comma and words *, and connected mechanism for operating both said*; and that the said Letters Patent should be read with these corrections therein that the same may conform to the record of the case in the Patent Office.

Signed and sealed this 8th day of January, A. D., 1924.

[SEAL.]

KARL FENNING,
Acting Commissioner of Patents.
